UNITED STATES PATENT OFFICE.

FRANKLIN E. ARNDT, OF GALION, OHIO, ASSIGNOR TO THE GALION IRON WORKS & MANUFACTURING COMPANY, OF GALION, OHIO, A CORPORATION OF OHIO.

HAND-WHEEL LOCKING DEVICE OR BRAKE.

1,105,236.

Specification of Letters Patent.

Patented July 28, 1914.

Application filed February 28, 1914. Serial No. 821,763.

To all whom it may concern:

Be it known that I, FRANKLIN E. ARNDT, a citizen of the United States, residing at Galion, in the county of Crawford and State 5 of Ohio, have invented certain new and useful Improvements in Hand-Wheel Locking Devices or Brakes, of which the following is a specification.

This invention comprehends certain new 10 and useful improvements in road machines of the type which employ a wheeled framework, draw bars suspended thereby and pivotally mounted so that they may be raised at their rear ends to the same elevation or one 15 higher than the other as required, a circle carried by the draw bars and rotatably adjustable, and a mold board and blade carried by the circle, the means for elevating the draw bars comprising suspension links, 20 relatively large hand wheels disposed in vertical planes to rotate about horizontal axes, and gearing connection between the hand wheels and vertically movable rack bars or the like to which the upper ends of the suspension links are connected. In this type of 25 machines, an operator's platform is provided immediately back of these hand wheels and it is customary to provide brakes engageable with the peripheries of the hand 30 wheels and usually releasable by means of foot treadles, whereby the operator may place his foot upon either of these treadles and release the brake so as to permit the hand wheel to turn in a direction to lower 35 the draw bar on one side or on both sides of the machine, or to be turned by the operator in a direction to raise the draw bar or draw bars according to whether one or both of the hand 40 wheels are manipulated. It is this hand wheel brake which forms the subject matter of the present invention.

The invention has for its primary object 45 a simple, durable and efficient friction operating hand wheel locking device, by the use of which the brake block is shoved square up against the rim of the hand wheel, pointing directly toward the axis or center of the wheel, whereby the wheel will be very firmly held in place and will effectively resist any pull on the hand wheel in either direction, positively not letting go until released by the foot treadle, which releases it very easily.

A further object of the invention is a hand 50 wheel brake of this type, the parts of which

are strong, capable of being easily made and installed and not liable to get out of order. And the invention also aims to generally improve devices of this class so as to render them more useful and commercially desirable. 60

With these and other objects in view, as will more fully appear as the description proceeds, the invention consists in certain constructions, arrangements and combinations of the parts that I shall hereinafter fully describe and claim. 65

For a full understanding of the invention, reference is to be had to the following description and accompanying drawing, in 70 which—

Figure 1 is a side elevation of my invention showing it in applied position, some of the parts of a road machine being shown in full lines and others in dotted lines. Fig. 2. 75 is a longitudinal sectional view of the device. Fig. 3 is a transverse section on the line 3—3 of Fig. 1. Fig. 4 is a fragmentary sectional view showing the brake shoe in engagement with the rim of the hand wheel. 80

Corresponding and like parts are referred to in the following description and designated in all of the views of the accompanying drawing, by like reference characters.

Referring to the drawing, the numeral 1. 85 designates one of the arched sills or side bars of the wheeled framework of a road machine, and 2 designates one of the draw bars designed to support the rotatable circle 3 carrying the mold board 4 and the reversible blade 5. 6 designates one of the suspension links hereinbefore referred to which is connected at its upper end to a vertically movable rack bar 7 operated by means of the large hand wheel 8 as is customary in this 90 type of machine. 95

In order to positively and securely hold the hand wheel as against accidental movement, I provide my improved friction locking device or brake, it being understood, 100 of course, that there is one of these devices for each hand wheel, but as they are identical in construction, a description of one of them will suffice for both. This device includes a casing 9 which is substantially rectangular in the present instance, and provided with an attaching member 10 formed to receive a bolt or other fastening device by which it is secured to the arched sill 1 on the downwardly inclined or obliquely dis- 105 110

posed rear portion thereof just back of and below the hand wheel 8, the casing being so disposed that the preferably wooden friction block 11 forming part of the brake device 5 will point toward and move in a radial direction toward and away from the center or axis of the hand wheel.

The brake block or shoe 11 is in the present embodiment of the invention, received 10 within a socket 12 formed in the upper end of a casting which also includes a longitudinally disposed rack bar 13, the rack bar and socket and the bracing web 14 which connects the two at their juncture, constituting 15 the plunger of the brake. The teeth 15 that are formed on one edge of the rack bar 13 below the web 14 mesh with the teeth of a spur pinion 16 journaled within the lower open end of the casing 9 on a transversely disposed spindle or axis 17 and the sleeve 18 of this spur pinion 16 has secured to it in any desired way, as by the lock joint 19, one end of a foot treadle 20 disposed to one side of the casing and extending rearwardly 20 therefrom, as best illustrated in Fig. 3. In the normal set position of the brake, the releasing treadle 20 extends in substantially horizontal position just above and spaced from the operators' platform 21.

The rack bar 13 is preferably in the form 25 of an I beam, as clearly illustrated in the drawing, and its lower end passes through a divided ledge or partition 22 formed within the casing 9 near the lower open end thereof and integral with the rear and side walls of the same. Mounted within the casing 9 are two coiled expansion springs 23, the same being disposed respectively on opposite sides of the channeled rack bar 13 30 and having their lower ends resting upon the ledge 22 while their upper ends press upon the lower side of the socket member 12, so that it will be understood that the tension of these springs is exerted upon 35 the plunger in a direction to move it toward the center of the hand wheel 8 and to press the brake shoe or block 11 positively and firmly against the rim of the wheel. Thus, the wheel will be firmly held and positively prevented from accidental movement 40 in either direction. The plunger will effectively resist a pull on the hand wheel either way and will positively not let go until the operator presses downwardly upon the foot treadle 20 which will manifestly turn the spur pinion 16 and draw the rack bar and the other parts of the plunger downwardly 45 against the tension of the expansion springs 23, this operation being very easily accomplished.

From the foregoing description in connection with the accompanying drawing, it will be seen that I have provided a very simple and efficient construction of friction locking device or brake for a road grader

hand wheel and one which may be very cheaply and easily manufactured and the parts capable of being readily assembled and not liable to get out of order.

While the accompanying drawing illustrates what I believe to be the preferred embodiment of my invention, it is to be understood that the invention is not limited thereto, but that various changes may be made in the construction, arrangements and proportions of the parts without departing from the scope of the invention as defined in the appended claims.

What I claim, is:

1. A brake of the character described, including a plunger, a casing in which said plunger is movable, the plunger being provided with rack teeth, a pinion meshing with said teeth and journaled in the casing, and a foot treadle on the outside of the casing and connected with said pinion to turn the same.

2. A brake of the character described, including a casing, a plunger movable therein and embodying a rack bar mounted medially of the casing, the casing being provided with a divided ledge through which the rack bar is movable, expansion springs mounted on opposite sides of said rack bar and bearing against the plunger and resting against the ledge, and means for moving said plunger in the casing against the tension of said springs.

3. A brake of the character described, comprising a casing formed near its lower end with a divided ledge, a plunger movable in said casing and including a rack bar movable through said ledge and also including a socket, a brake shoe mounted in said socket, coiled expansion springs mounted within the casing on opposite sides of said rack bar and resting upon said ledge and bearing against the socket, a pinion mounted within the casing and meshing with said rack bar, and means for turning said pinion whereby to move the plunger in the casing against the tension of said springs.

4. A brake of the character described, comprising a casing, a plunger movable therein and consisting of a casting having a socket at one end, a bar of I beam formation formed on one edge with teeth, and a brake shoe mounted in the socket, the casing being formed near one end with a divided ledge and the bar being movable through said ledge, a pinion journaled in said casing and meshing with the teeth of said bar, and a foot treadle operatively connected with said pinion and disposed to one side of the casing on the exterior thereof, as and for the purpose set forth.

5. A brake of the character described, including a casing, a plunger movable therein and embodying a rack bar mounted medially of the casing, expansion springs mounted

on opposite sides of said rack bar within the casing and bearing against the plunger, and reacting against portions of the casing, and means for moving said plunger against the tension of said springs.

6. A brake of the character described, including a casing, a plunger movable therein and embodying a rack bar mounted medially of the casing, expansion springs mounted on opposite sides of said rack bar within the casing, said plunger also embodying a brake-block receiving-socket, and the springs bearing against said socket and reacting against portions of the casing, and means for moving said plunger in the casing against the tension of said springs.

7. A brake of the character described including a casing, a plunger movable therein and embodying a rack bar, a pinion mounted within the casing and meshing with said rack bar, and a foot treadle operatively connected to said pinion.

8. A brake of the character described com-

prising a casing formed near its lower end with a divided ledge, a plunger movable in said casing and including a rack bar movable through said ledge, coiled expansion springs mounted within the casing on opposite sides of said rack bar and resting upon said ledge and operating upon the plunger to move it in one direction, a pinion meshing with said rack bar, a transversely disposed spindle journaled in the casing, and carrying said pinion, and a foot treadle mounted on said spindle at one end thereof outside of the casing, the pinion being provided with a sleeve, and the foot treadle having a lock joint connection with said sleeve, and for the purpose set forth.

In testimony whereof I affix my signature in presence of two witnesses.

FRANKLIN E. ARNDT.
